(57) **CLAIM**

The ornamental design for a scope cover, as shown and described.

DESCRIPTION

FIG. 1 is a top plan view of a scope cover;

FIG. 2 is a left elevation view thereof;

FIG. 3 is a right elevation view thereof;

FIG. 4 is a rear elevation view thereof;

FIG. 5 is a front elevation view thereof;

FIG. 6 is a bottom plan view thereof; and,

FIG. 7 is a top plan view thereof in an open configuration. The two types of shading in the figures represents a difference in appearance.
